UNITED STATES PATENT OFFICE

VERNON ALBERT SCOTT, OF TORONTO, ONTARIO, CANADA, ASSIGNOR OF FIFTY-ONE
PER CENT TO URBAN DAVID CLARK, OF TORONTO, CANADA

COIN-CONTROLLED OPERATING MECHANISM FOR VENDING MACHINES AND THE LIKE

Application filed October 31, 1927, Serial No. 230,001. Renewed July 25, 1929.

This invention relates to a coin-controlled operating mechanism for vending machines and the like, as described in the present specification and illustrated in the accompanying drawings which form part of the same.

The invention consists essentially of the novel features pointed out broadly and specifically in the claims for novelty following a description containing an explanation in detail of an acceptable form of the invention.

The objects of the invention are to construct a coin-controlled operating device of simple and dependable construction, positive of operation, and one especially adapted for vending machines.

In the drawings, Figure 1 is an outside plan view of the base plate.

Figure 2 is an inside plan view of the base plate.

Figure 3 is an inside plan view of the coin-driving disc.

Figure 4 is a side view of Figure 3.

Figure 5 is a fragmentary side view of Figure 1.

Figure 6 is an end elevation view of the coin-controlled mechanism complete.

Like numerals of reference indicate corresponding parts in the various figures.

Referring to the drawings, 35 is a circular disc or base plate having the central opening 36 surrounded by the raised bosses 37 and 38 which project out from the outer and inner faces respectively, of said disc; 39 are raised peripheral portions of equal width formed on the inner face of the disc and spaced to leave the gaps 41 and 42.

43 is a second disc or coin-driving plate having the outer boss 51 and the inner central bearing 44 sized to fit and rotate in the hole 36 of the base plate 35, and formed with the raised annular portion 45 projecting out from the inner face thereof; the portion 45 is depressed in at 46 to slightly more than the thickness of the prescribed coin or coins, 45 designated by the numeral 74. The depression 46 forms with the base plate when the coin-driving plate is assembled to or upon said base plate, the coin-chamber or magazine. The raised annular portion 45 is made 50 to fit in the annular groove 48 formed be-

tween the raised boss 38 and the peripheral portions 39, while the inner face of said disc 43 bears or slides upon the boss 38 and the portions 39. The disc 43 is rigidly mounted upon a shaft 49 as with a set screw 49A 55 threaded through the boss 51 and engaging said shaft. The shaft is introduced through the opening 36 of the base plate and the disc 43 retained in its assembled position upon said base plate as with the collar 52 held 60 rigidly upon the bearing 44 by means of the set screw 53. The shaft 49 extends beyond the end of said bearing 44 to receive a suitable gear 54, the gear being rigidly secured upon the shaft in any suitable manner, as with 65 a pin 55 passed through said gear and inserted into a hole 55A made in said bearing 44, as shown in Figure 6.

56 are metal straps secured to the base plate and formed to be fastened to the vending machine. The shaft 49 is made long enough to extend through the wall of the vending machine and to receive the crank 57. The base plate is therefore fixed while the disc 43 can be rotated upon said base plate by 75 turning the crank 57.

60 is a short lever rigidly carried by a spindle 61 rotating in brackets 62 carried by the outer face of the base plate 35; 59 is a pin sliding in said base plate and having the top end slotted in as at 65 to receive the end of the lever 60; 64 is a small pin passed through the pin 59 above the lever 60 and projecting out on each side thereof; 63 are tensioned springs secured at the top to the pin 64 and secured at the bottom to the base plate, so that the action of the springs is to swing or tend to swing the lever 60 downwardly. The spindle 61 rigidly carries the fingers 66 which pass through slots 67 made through the base 80 plate 35. The downward travel of the pin 59 under the action of the tensioned springs 63 is limited or checked by the engagement of the fingers 66 with the end of the slots 67, as best shown in Figure 5.

85 The fingers 66 are made long enough to project beyond the inner face of the base plate, or in other words, to project into the groove 48, so that as the coins are forced or slid within said groove by the rotation of 100

the disc 43, their engagement with the fingers will tilt these, tilt the lever 60, and raise the pin 59 until its lower end face 68 lies between the inner and outer faces of said base plate. The peripheral edge of the disc 43 is depressed in at 69 to provide the shoulders 70 and 71 which limit or check the rotation of the disc relative to the base plate by their engagement with the pin 59. 5 Therefore, unless the prescribed number of coins are inserted into the coin chamber to engage the ends of the fingers 66 when the disc is rotated in the direction of the arrow, the pin 59 will lie in the path of the shoulder 10 70 and thus check the rotation of said disc. If on the other hand, the prescribed number of coins are inserted into the coin chamber through the slot or gap 41, the coins will engage the fingers and cause the pin 59 to be 15 lifted, the disc being now free to rotate. The base plate is so secured in the vending machine that the coin slot or gap 41 preferably lies slightly to one side of a vertical line drawn through the centre of said base 20 plate, or in about the position shown in Figure 1. The shoulder 71 in the disc 43 must be so disposed relative to the coin chamber that the gap 41 will open into or communicate 25 with the coin chamber when the shoulder 71 30 engages the pin 59. The shoulder 72 must be so disposed relative to the shoulder 70 and the distance between the pin 59 and the fingers 66 be such that the shoulder 70 will engage the pin 59 before the shoulder 72 35 engages the fingers, or in other words, the shoulder 70 must engage the pin 59 before the shoulder 72 reaches the position of the fingers 66; but the arcual distance between the shoulders 70 and 71 must be more than 40 the clearance left between the coins and the shoulder 72, so that the engagement of the coins with the fingers will cause the pin 59 to move out of the way of the shoulder 70 when the disc 43 is rotated. When reaching 45 the gap 42, the coins fall out therethrough.

53A is a spring secured at one end to the gear 54 by means of a pin 81 and anchored at the other end to the vending machine and disposed and tensioned to normally retain the shoulder 71 of the disc 43 in engagement with the pin 59.

Operation.—When the disc 43 is in its normal position, the shoulder 71 is in engagement with the pin 59, and the coin gap 41 55 communicates with the coin chamber 46. The two coins 74 are dropped into the vending machine slot, falling down through a coin chute 77; the coins enter the coin-controlled mechanism through the gap 41, sliding down in the groove or channel 48 until they are arrested by the fingers 66. By rotating the crank 57, the upper coin, that is the coin last inserted, is engaged by the shoulder 72, forcing the lower coin against the fingers 66 and raising the pin 59 out of the

path of the shoulder 70; when the coins have been forced or slid to opposite the gap 42, they fall out of the mechanism. The pin 59 now rides upon the inner face of the disc until the shoulder 71 passes the pin when 70 the pin is forced outwardly into the gap 69.

What I claim is:

1. In a coin-controlled operating mechanism for vending machines, a base plate having a circularly-arranged groove on one face thereof and a coin inlet and a coin outlet opening into said groove, a coin-driving disc having a circularly-arranged projection sliding in said groove and depressed to form with said base plate a coin chamber, a pin 80 slidably mounted in said base plate and springheld in locking engagement with said base plate, a pivoted finger extending into the path of said coin chamber, and a lever rigid with said fingers and operatively engaging said pin.

2. In a coin-controlled operating mechanism for vending machines, a base plate having a coin inlet and a coin outlet, a disc rotatably mounted on said base plate and recessed, 90 to form therewith a movable coin chamber, a pin slidably mounted in said base plate at right angles to the plane thereof and springheld in locking engagement with said disc, and coin-controlled means lying in the path 95 of said movable coin chamber for moving said pin out of locking engagement.

3. In a coin controlled operating mechanism for vending machines, a base plate having a coin inlet and a coin outlet, a coin driving disc rotatably mounted on said base plate and having a notch in the peripheral edge thereof, a pin slidably mounted in said base plate and springheld in said notch, a lever pivotally mounted on said base plate and extending into the path of the coins and adapted to remove said pin from said notched recess on engagement with said coins when said disc is rotated.

4. In a coin controlled operating mechanism for vending machines, a base plate having a coin inlet and a coin outlet, a coin driving disc rotatably mounted on said base plate and having a peripheral recess and a coin chamber adapted to receive the coins from said inlet and deliver same to said outlet on rotation of said disc, a pin slidably mounted in said base plate and springheld in said peripheral recess, a lever pivotally mounted on said base plate and extending into said coin chamber and adapted to be actuated by coins in said chamber to remove said pin from said peripheral recess on the rotation of said disc.

5. In a coin controlled operating mechanism for vending machines, a base plate having a coin inlet and a coin outlet, a disc rotatably mounted in said base plate and recessed to form therewith a movable coin chamber, a pin slidably mounted on said 130

base plate and sized to project into a transverse groove formed in the peripheral edge of said disc, a spring adapted to normally retain said pin projecting into said groove, and a lever pivotally mounted on said base plate and slidably engaging at one end said pin and rigidly carrying a finger at the other end, said finger normally lying in the path of said coin chamber.

10 Signed at the city of Toronto, this 10th day of March, 1927.

VERNON ALBERT SCOTT.
